UNITED STATES PATENT OFFICE.

IVERT LARSEN, OF CHICAGO, ILLINOIS, ASSIGNOR OF ONE-HALF TO
ROBERT G. ARMSTRONG, OF CHICAGO, ILLINOIS.

HAME.

SPECIFICATION forming part of Letters Patent No. 772,314, dated October 11, 1904.

Application filed April 7, 1902. Serial No. 101,646. (No model.)

To all whom it may concern:

Be it known that I, IVERT LARSEN, of Chicago, in the county of Cook and State of Illinois, have invented certain new and useful 5 Improvements in Hames; and I do hereby declare that the following is a full, clear, and exact description thereof, reference being had to the accompanying drawings, and to the letters of reference marked thereon, which form a 10 part of this specification.

This invention relates to improvements in adjustable hames for horse-collars, and refers more specifically to improvements designed to permit of longitudinal adjustment of the 15 hames to adapt the same to collars of different lengths.

Among the objects of my invention is to simplify the construction of such adjustable hames and at the same time strengthen the 20 connections between the adjustable parts of the hames.

In the drawings, Figure 1 is a front elevation of a set of adjustable hames made in accordance with my invention, showing the same 25 in position on a collar on which the same are adapted to be used. Fig. 2 is a fragmentary side elevation of one of the hames, illustrating the manner of adjustably connecting the upper and lower slidably-connected parts of 30 the hames. Fig. 3 is a longitudinal section taken on the line 3 3 of Fig. 2. Fig. 4 is a cross-section taken on line 4 4 of Fig. 3. Fig. 5 is a cross-section taken on line 5 5 of Fig. 3.

As shown in the drawings, A designates a 35 collar of that type which is separated at its lower or throat end and the side members of which are flexibly joined at the upper or wither end of the collar, whereby said side members may be separated for the purpose of 40 applying the collar to and removing the same from a horse. The lower or divided ends of the collar are held or locked in place by the hames and the locking or coupling connections thereof, as will hereinafter more fully appear. Said hames consist of two similar 45 side members, each comprising an upper tubular part or section B and a lower tubular part or section B', which are adjustably connected by devices constituting the present in-

vention. Said hames occupy the usual depression between the fore and aft wales of the collar and are secured to the collar in any suitable manner, as by means of loops A', connected with the collar and encircling the hames at the upper part thereof, as shown in 55 Fig. 1.

Now describing the adjustable connection between the upper and lower sections B B' of the hames, whereby said hames may be made to fit longer or shorter collars, said connection is made as follows: The upper tubular member of each hame has telescopic connection with the lower tubular member thereof, and, as herein shown, said upper member fits within the lower member. The outer telescopic member B' of the telescopically-connected parts is provided with a slit b, which extends from the extreme end thereof some distance inwardly or downwardly. C designates a clamping-sleeve which surrounds the 70 split end of the lower section of the hames and is secured permanently thereto in any suitable manner, as by brazing. Said sleeve is longitudinally split in line with the slit b of the section B' and is provided at each side of 75 said split portion with laterally-directed parallel lugs C' C', through which extends a clamping bolt or screw C², said bolt or screw passing freely through one of the lugs and having screw-threaded engagement with the 80 other. With this construction when the clamping bolt or screw is tightened the lugs are brought together, and the outer member B' of the telescopic connection is contracted in close circumferential contact with the inner member B and binds said parts firmly together, so as to prevent relative endwise movement thereof.

In addition to the clamping-sleeve above described for connecting said telescopic parts of 90 the hames I have provided a supplemental clamping device which engages said parts below the clamping-sleeve and co-operates therewith to make more rigid the connection between said parts. Said supplemental clamping device consists of a screw-bolt D, which extends through a suitable opening in the wall 95 of the outer telescopic member and through a

boss raised or elevated from said wall and also through an elongated slot b' , formed in the inner telescopic member B. Said clamping-screw has screw-threaded engagement at its 5 inner end with a clamping-nut D', located within the inner tubular member and having sliding engagement therewith. The nut is made rounded or parti-cylindric on the side thereof adjacent to the bolt D and engages the inner cylindric surface of the inner tubular member of the connection. Said nut is provided on its rounded side with a raised rib d , which enters the slot b' of the inner tubular member B of the telescopic connection, 10 and said rib prevents the clamp-nut from turning or rotating in said member. Said nut is made of a width to extend entirely across the tubular section B and engages the wall of the tube opposite to the slot b' , so that when the nut is inserted into the inner tubular part of the connection it has close-fitting engagement therewith and is held always in position for connection with the clamping-screw D should said clamping-screw be entirely removed from the block. In other words, when engaged with the slot b' the rib d prevents the nut from turning or rotating in said tubular section, and the bearing or contact on both sides of said tubular section 15 prevents said rib becoming disengaged from said slot b' . The clamping-nut is cut away at its end in the manner indicated in Fig. 5 for the purpose of lightening the same. Said nut is placed inside the tubular section B of the 20 hames from the lower end thereof, and a stop-screw b^2 is inserted in the wall of said section in the manner shown in Fig. 3 to prevent accidental separation of said parts. The combined clamping devices shown, consisting of the clamping-sleeve C and the clamping bolt and nut D and D' are not herein broadly claimed, but are made the subject of claims 25 of an application of Robert G. Armstrong, filed of even date herewith.

45 An important advantage of the construction of the clamping-nut D' and its relation to the inner tubular section is that said nut, together with the clamping-bolt D, affords a very rigid clamping structure, due to the ample contact-surfaces of the nut with the inner tubular member of the connection. A further important advantage of the construction is that the nut is maintained always in position for engagement therewith of the 50 clamping-bolt and cannot turn or rotate in a manner to throw the bolt-aperture thereof out of line with the slot b' , through which the bolt is passed to engage the same with the nut.

The hames are hinged at their upper ends 60 by means of a pintle b^3 , extending through registering apertures b^4 b^5 in overlapping or crossed parts B^5 B^6 of said upper sections of the hames.

The lower ends of the hames are locked to-

gether by means of a locking-bolt H, which 65 is pivoted to one of the hames and adapted to engage a locking member in a socketed casing H', attached to the lower end of the other hame. The form of coupling shown is like that illustrated in the prior United States Letters Patent to Robert G. Armstrong, issued February 26, 1896, No. 555,279, and need not be herein further described.

It is obvious that many changes in the structural details may be made without departing from the spirit of my invention, and I do not wish to be limited to the specific details except as hereinafter made the subject of specific claims.

I claim as my invention—

1. A hame for a horse-collar, comprising two telescopic parts or sections, the outer section of which is longitudinally slotted, means for clamping said outer slotted section on the inner section and supplemental clamping means for said telescopic sections embracing a short nut in the inner section and a bolt which extends transversely through the walls of both the said sections at one side of the hame and having screw-threaded engagement with said nut.

2. A hame for a horse-collar, comprising two telescopic tubular sections, the outer section of which is longitudinally slotted and provided with an aperture and the inner section 95 of which is provided with a longitudinal slot, a clamping-sleeve surrounding said outer section, means co-operating with said sleeve for clamping said outer section on the inner section and supplemental clamping means comprising a clamping-nut located within the tubular inner section and a bolt extending through and closely fitting said aperture in the wall of the outer section and through said longitudinal slot in the inner section, and having screw-threaded engagement with the said bolt, whereby said bolt is immovable longitudinally of the outer section and the inner section may move endwise in the outer section relatively to said bolt.

3. A hame for a horse-collar, comprising two telescopic tubular sections, the outer section of which is longitudinally slotted and provided with an aperture, and the inner section of which is provided with a longitudinal slot, 115 means for clamping said outer slotted section on the inner section and supplemental clamping means for said telescopic sections comprising a clamping-nut in the inner section, a headed bolt extending through said aperture in the wall of the outer section and through said longitudinal slot in the adjacent wall of the inner section and having screw-threaded engagement with said nut, and a washer on said bolt between its head and the outer section and shaped on its inner face to fit the outer section.

4. A hame for a horse-collar comprising

two telescopic parts or sections the outer section of which is longitudinally slitted, means for clamping said outer slitted section on the inner section, a clamping-nut in said inner section which has longitudinally-sliding engagement therewith and has bearing on two opposing sides with the walls of the inner section, a bolt extending through the walls of said sections, and having screw-threaded engagement with said nut, and means preventing rotation of said nut in said inner section when the bolt is disengaged therefrom.

5 5. A hame for a horse-collar comprising two telescopic parts or sections, the outer section 15 of which is longitudinally slitted, means for clamping said outer slitted section on the inner section, and supplemental clamping means for said telescopic sections, comprising a clamping-nut in the inner section and a bolt 20 extending through the walls of said sections, and having screw-threaded engagement with said clamping-nut, said inner section being provided with a longitudinal slot and the clamping-nut being provided with a projection 25 which enters said slot.

6 6. A hame for a horse-collar comprising two telescopic parts or sections, the outer section of which is longitudinally slitted, means for clamping said outer slitted section on the inner section, and supplemental clamping means for said telescopic sections comprising a clamping-nut in the inner section and a bolt 30 extending through the walls of said sections and having screw-threaded engagement with said clamping-nut, said inner tubular member being provided with a longitudinal slot and the clamping-nut being provided with a longitudinal rib which enters the slot and bearing at its side remote from said rib against the 35 wall of said inner section.

7 7. A hame for a horse-collar comprising two tubular telescopic parts or sections, the outer part or section of which is longitudinally slitted, means for clamping said outer slitted 40 section on the inner section, and supplemental clamping means for said telescopic sections comprising a clamping-nut within the inner section and a bolt extending through the walls of said sections and having screw-threaded engagement 45 with said clamping-nut, said inner section being provided with a longitudinal slot through which the bolt extends, and the nut being provided with a rib or projection which enters and has sliding engagement 50 with said slot, said nut engaging on its side remote from said rib the wall of said inner 55

section, and a removable stop for retaining said nut in said inner section.

8 8. A hame for a horse-collar comprising two telescopic parts or sections, and means for clamping said sections together comprising a clamping-nut in the inner section and a bolt 60 extending through the walls of said sections and having screw-threaded engagement with said nut, and means preventing rotation of 65 said nut in said inner section when the bolt is removed therefrom.

9 9. A hame for a horse-collar comprising two telescopic, tubular, parts or sections and means for clamping said sections together comprising 70 a nut in the inner section and a bolt extending through said sections and having screw-threaded engagement with said nut, said nut being provided on two of its opposite sides with rounded surfaces which have sliding 75 engagement with the inner surface of the inner section.

10 10. A hame for horse-collars comprising two telescopic, tubular, parts or sections, and means for clamping said sections together 80 comprising a clamping-nut in the inner section and filling the same from side to side and a bolt extending through the walls of said sections and having screw-threaded engagement 85 with said clamping-nut, said inner section being provided with a slot through which the bolt extends and the nut being provided with a rib or projection which enters said slot and has longitudinal sliding engagement therewith. 90

11 11. A hame for horse-collars comprising two telescopic parts or sections, and means for clamping said sections together comprising a clamping-nut in the inner section and a bolt extending through the walls of said sections and having screw-threaded engagement 95 with said clamping-nut, said inner section being provided with a slot through which the bolt extends, and the nut being provided with a rib or projection which enters said slot and 100 has longitudinal sliding engagement therewith, and said nut having guiding engagement with the wall of the inner section of the side of the block remote from said rib. 105

In testimony that I claim the foregoing as my invention I affix my signature, in presence of two witnesses, this 1st day of April, A. D. 1902.

IVERT LARSEN.
